Application October 24, 1933, Serial No. 694,994

7 Claims. (Cl. 280—3)

This invention relates to shipping containers of the kind used by railroads in the transportation of freight in less than carload lots. Such containers are ordinarily proportioned and designed for close arrangement in serial order on flat freight cars, and adapted to be transferred sidewise from the cars to station platforms or to motor trucks, trailers, etc., and vice versa.

The chief aim of our invention is to make possible the transfer of shipping containers of the kind referred to without necessitating the aid of power hoisting devices or lifting cranes, (which are not always available, particularly at wayside railway stations), through individual incorporation with the containers, of manually-operable propelling mechanism to effect either straight-away or curvilinear progression of the containers.

Our invention is moreover directed toward securing the above desideratum in a manually-operative propelling mechanism which is compact and so organized and allocated that it does not interfere with the usual close arrangement of the containers on the railway cars or trucks.

Still other objects and attendant advantages of this invention will be manifest from the detailed description which follows of the drawings, wherein Fig. I is a side elevation of a shipping container conveniently embodying our invention in one form.

Fig. II is an end elevation of the container with a portion broken out and in section to expose parts which would otherwise be hidden.

Fig. III is a plan section of the container with the center portion thereof broken out.

Fig. IV is a fragmentary view of the container partly in side elevation and partly in vertical section.

Fig. V is a fragmentary detail sectional view taken as indicated by the arrows V—V in Figs. III and IV and drawn to a larger scale.

Fig. VI is a detail view of a removable handle for actuating the propelling mechanism of the container.

Fig. VII is a fragmentary view showing in plan a container embodying a slightly modified form of propelling mechanism.

The shipping container delineated in Figs. I—VI is, generally speaking, of standard construction, the same having solid end walls 11, and side walls 12 with doors 13 by which access is had to the interior. In accordance with our invention we mount the container on a chassis 14 which comprises two laterally-spaced endless sprocket chain traction belts 15, 16 that extend lengthwise of the opposite ends of the container.

The driving sprockets 17, 18 for these traction belts are respectively secured to aligned sections 19, 20 of a split shaft having journal support in suitable bearings 21, 22 afforded by the chassis. Fast on the contiguous inner ends of the shaft sections 19, 20 are opposing bevel gear wheels 23, 24 respectively. At right angles to the split sprocket shaft and extending from one side 12 to the other of the container below the floor 25 of the latter is an actuating shaft 26 whereof the polygonal ends 27, 28 project somewhat beyond said container sides 12. The shaft 26 is free within a split sleeve composed of two sections 29, 30 having journal support in bearings 31, 32 and 33 of the chassis 14. As shown, the sleeve sections 29, 30 respectively terminate in squared ends 34, 35 somewhat inward of the polygonal ends 27, 28 of the shaft 26 which latter carries a bevel pinion 36 that meshes with the bevel gear wheel 24 on the sprocket shaft section 20. Affixed to the inner end of the sleeve section 29 are a bevel pinion 37 which meshes with the bevel gear wheel 23 on the other sprocket shaft section 19 and a spur pinion 38 which meshes with a mating pinion 39 on one end of another cross shaft 40 which is journaled in the bearings 31, 32 at a level above the shaft 26. At its opposite end, the shaft 40 carries a spur pinion 41 like the pinion 39, which meshes with a companion spur pinion 42 on the inner end of the sleeve section 30.

At 43 is shown an actuating handle, which, within a bifurcation at its lower end, carries, with capacity for independent rotation, a pair of ratchet wheels 44 and 45 respectively having axial polygonal openings to fit the polygonal ends 27, 28 and 34, 35 respectively of the actuating shaft 26 and the sleeve sections 29, 30. A pair of doubled-ended reversing pawls 46, 47 for cooperating respectively with the ratchet wheels 44, 45, are independently pivoted on a pin 48 which extends crosswise of the bifurcation of the handle 43 above said ratchet wheels. Influential upon the pawls 46, 47 are arcuate bale-like springs 49, 50 respectively, each having three notches for selective engagement with fixed studs 51, 52 on the handle 43.

To manipulate the container, the actuating handle 43 is applied for example to the corresponding polygonal ends of the shaft 26 and the sleeve section 29 at one side of the container as shown in Figs. I, III and V. The pawls 46, 47 are next set by adjustment of the bale springs 49, 50 in accordance with the direction in which the container is to be progressed. For straight-away progression of the container in the direction in-

dicated by the arrow in Figs. II and III, the pawls 46, 47 are both swung to the position shown in Fig. I with their right hand ends active upon the ratchet wheels 44, 45. Accordingly, as the han-
5 dle is swung back and forth, both the operating shaft 26 and the sleeve section 29 are rotated anti-clockwise with resultant concurrent actuation of the traction belts 15, 16 to progress the container straightaway as in the indicated direc-
10 tion through motion imparted to them by the intermeshing bevel gear couples 24, 36 and 23, 31. By setting the pawls 46, 47 so that their left hand ends simultaneously engage the ratchet wheels 44, 45, and thereupon swinging the han-
15 dle 43 as before, the container will obviously be progressed straight-away in the direction oppo-
site to that shown by the arrows in Figs. II and III. Again, with the pawl 46 in neutral as in Fig. VI and the right hand end of the pawl 47 in
20 action, only the sleeve section 29 will be turned anti-clockwise through cooperation of the bevel gear 23 and pinion 37 with consequent impartation upon swinging of the handle 43, of movement to the traction belt 15 alone, the container being
25 thereby caused to turn leftward while the traction belt 16 remains idle. Similarly, with the pawl 47 in neutral and the left hand end of the pawl 46 in action, in Fig. VI, the container will be turned rightward incident to progression in the
30 direction of the arrow in Fig. III upon actuation of the handle 43. To operate the traction belt 16 alone, the pawl 47 is placed in neutral and either the right hand or left hand end of the pawl 46 placed in action, whereby, upon swinging the
35 handle, the container is correspondingly steered either to the right or left incident to its progression with the traction belt 15 idle. By applying the handle to the corresponding ends of the transverse shaft and sleeve at the opposite sides
40 of the container, and proceeding as above ex-
plained, the container may be progressed either forwards or backwards or along curvilinear paths either leftward or rightward in identically the same manner as before, the movements of the
45 sleeve section 30 being communicated to the sleeve section through the spur gear couples 41, 42 and 38, 39 and the cross shaft 40. Thus, through our invention, it is possible for one man alone to manipulate the container as desired or
50 required to move it onto or off a railway car, station platform or truck, the operation being com-
paratively easy by virtue of the reducing differ-
ential ratio of the bevel gear couples 23, 31 and
55 24, 36. While the actuating shaft 26 may, if de-
sired, be otherwise located, we prefer to place it near one end of the container so that during the actuation of the handle, the operator can see around the corresponding corners of the container and better direct its progress.
60 The modified form of our invention shown in Fig. VII is like that of Figs. I-VI but capable of operation from one side only of the container. In this case, the actuating shaft 26a is compa-
65 ratively short with only one of its ends 27a poly-
gonally configured and projecting beyond a door side 12a of the container. As before, the shaft 26a carries a bevel pinion 36a that meshes with a bevel gear wheel 24a on the sprocket shaft section 20a. Moreover in this case, but one sleeve
70 29a is employed, the same having its ends squared as at 34a, carrying a bevel pinion 37a which meshes with a bevel gear wheel 23a on the sprocket shaft section 19a for the traction belt 15a, the sleeve section 30, the spur pinions 38, 39, 41 and
75 42 and the shaft 40 of the first described em-

bodiment being entirely dispensed with here. All other identical features not specifically referred to in the modification are identified with the same reference numerals used in Figs. I-VI with the addition, in each instance, of the distinguishing character "a". The operation of the modified form of our invention is obviously identical with that of the first described embodiment. By reason of the allocation of the connections for attachment of the actuating handle 43 in both cases at the door sides 12 of the containers, the closed ends 11 of the latter are left free of any projections which might tend to interfere with the desired close arrangement of the containers on the railway cars or motor trucks.

Having thus described our invention, we claim:

1. In a shipping container of the character described, a supporting chassis with laterally-spaced endless traction belts; a divided drive shaft composed of sections with sprockets for the respective traction belts; opposing bevel gear wheels on the contiguous ends of the sprocket shaft sections; an actuating shaft with a polygonal end accessible at one side of the container; 20 a bevel pinion on said actuating shaft in mesh with one of the bevel gear wheels; a sleeve free on the actuating shaft terminating in a polygonal end somewhat inward of the polygonal end of the actuating shaft and carrying a bevel pinion in mesh with the other of the aforesaid gear wheels; and means attachable to the squared ends respectively of the actuating shaft and sleeve whereby the traction belts may be either 25 concurrently or individually operated manually to effect straight-away or curvilinear progression of the container.

2. In a shipping container of the character described, a supporting chassis with laterally-spaced endless traction belts; a divided drive 40 shaft composed of sections with sprockets for the respective traction belts; opposing bevel gear wheels on the contiguous ends of the sprocket shaft sections; an actuating shaft with polygonal ends respectively accessible at opposite sides of the container; a bevel pinion on said actuating shaft in mesh with one of the bevel gear wheels; a divided sleeve with its sections free on the actuating shaft, one of the sleeve sections carrying a bevel pinion in mesh with the other of the two aforesaid beveled gear wheels, and both terminating respectively at opposite sides of the container in polygonal ends somewhat inward of the polygonal ends of the actuating shaft; gearing connecting the two sleeve sections for movement in unison; and means attachable to the contiguous polygonal ends respectively of the actuating shaft and its sleeves at opposite sides of the container, whereby the traction belts may be either concurrently or selectively operated 50 manually to effect straight-away or curvilinear progression of the container.

3. In a shipping container of the character described, a supporting chassis with laterally-spaced endless traction belts; a divided drive 65 shaft composed of sections with sprockets for the respective traction belts; opposing bevel gear wheels on the contiguous ends of the shaft sections; an actuating shaft with a polygonal end accessible at one side of the container; a bevel pinion on said actuating shaft in mesh with one of the bevel gear wheels; a sleeve free on the actuating shaft carrying a bevel pinion in mesh with the other of the two bevel gear wheels, said sleeve terminating in a polygonal end some- 70 75 75

what inward of the polygonal end of the actuating shaft; and an actuating handle with selective reversible ratchet means, attachable to the polygonal ends respectively of the actuating shaft and its sleeves whereby the traction belts may be either concurrently or individually operated manually to effect straight-away or curvilinear progression of the container.

4. In a shipping container of the character described, a supporting chassis with propelling means including laterally-spaced endless traction belts; and manual operating means comprising ratchet wheels coordinated respectively with said traction belts, an actuating hand lever, reversible pawls on said lever to cooperate respectively with the ratchet wheels; and means whereby said pawls may be set to determine concurrent movement of the traction belts for straightaway progression of the container either forwards or backwards, or to determine individual movement of the traction belts for curvilinear progression of the container either to the right or to the left.

5. In a shipping container of the character described, a supporting chassis with propelling means including a pair of laterally spaced endless traction belts; and manual operating means accessible for actuation at opposite sides of the container and comprising ratchet wheels coordinated respectively with said traction belts, an actuating hand lever, reversible pawls on said lever to cooperate respectively with the ratchet wheels and means whereby said pawls may be set to determine concurrent movement of the traction belts for straightaway progression of the container either forwards or backwards, or to determine individual movement of the traction belts for curvilinear progression of the container either to the right or to the left.

6. In a shipping container of the character described having solid end walls and access doors in its opposite side walls, a supporting chassis with propelling means including a pair of laterally-spaced endless traction belts; and manual operating means accessible for actuation at the door sides of the container, comprising ratchet wheels coordinated respectively with said traction belts, an actuating hand lever, reversible pawls on said lever to cooperate respectively with the ratchet wheels, and means whereby said pawls may be set to determine concurrent movement of the traction belts for straightaway progression of the container either forwards or backwards, or to determine individual movement of the traction belts for straight-away or curvilinear progression of the container either to the right or to the left.

7. In a shipping container of the character described, a supporting chassis with propelling means including a pair of laterally-spaced endless traction belts, drive wheels for said belts and drive shafts respectively for the drive wheels; and manual operating means including ratchet wheels coordinated respectively with the drive shafts, an actuating hand lever, reversible pawls on said lever to cooperate respectively with the ratchet wheels; and means whereby said pawls may be set to determine concurrent movement of the traction belts for straightaway progression of the containers either forwards or backwards, or to determine individual movement of the traction belts for curvilinear progression of the container either to the right or to the left.
